UNITED STATES PATENT OFFICE.

ARTHUR E. SMALL, OF CHICAGO, ILLINOIS, ASSIGNOR TO UNION METAL PRODUCTS COMPANY, OF CHICAGO, ILLINOIS, A CORPORATION OF DELAWARE.

HOPPER DOOR FOR RAILWAY CARS.

Application filed February 23, 1928. Serial No. 256,268.

This invention relates to railway cars and more particularly to hinged doors which form a part of the floor or load retaining means which are swingable to permit the discharge of the lading and has for its object the improvement of the attachment of the hinge member (or other transverse member) to the door proper, and to strengthen the reinforcing flange, and, furthermore, to strengthen the relation between the body of the door, the hinge and the reinforcing flange.

In the drawings:

Fig. 1 shows a typical application of my improvement to a door.

Fig. 2 is a section on line 2—2 of Fig. 1.

Fig. 3 shows a detail of the hinge construction.

Figs. 4 to 11 inclusive show modified forms described hereafter.

The usual hopper door made of a rolled metallic plate or of cast metal has a depending flange 2—3 around its perimeter to stiffen up the sides of the door so that when the transverse hinge or beam 4 is secured to the body 5 of the plate this flange must be cut away or slotted or the transverse member offset to permit it to pass the flange.

My invention is an improvement on such constructions and consists in splitting a portion of the flange 2 away from the body 5 of the door and bending it parallel to the transverse member 4 and securing it thereto (6) and providing apertures therein which register with apertures in the transverse member for the hinge pin.

When the flange is slotted or cut away, as mentioned above, the flange is materially weakened so that the side of the door is not stiffened, as desired, but with my arrangement the flange is not weakened; in fact, it is strengthened by being attached to the transverse member.

In Figs. 1 and 2 the flange 2 is cut away from the body 5 of the door and divided and the divided portions bent inwardly to form the reflanges or extensions 7—8 which are preferably secured to the hinge (or other transverse member 4) and the said hinge or transverse member is preferably secured to the body of the door (by rivet 9) so as to obtain a compact relation between the flange 2, the body 5 of the door and the transverse member 4. If the transverse member is a

hinge it is provided with apertures 10 to accommodate the hinge pin 11.

Fig. 3 shows the relation of the door body 5, the flange 2, the reflange 7—8 and the hinge strap 4. The usual center sill and top cover plate and hinge butt or bracket are shown.

In Figs. 4 and 5 the extensions or reflanges 7—8 are provided adjacent each opposite end of the hinge strap.

In Figs. 6 and 7 the extensions or reflanges 13—14 are bent outwardly and secured to the transverse member 4 and both elements are provided with registering apertures to accommodate a hinge pin.

Figs. 8 and 9 show the extensions 13—14 perforated (15) for a hinge pin with a ferrule or spreader 16 positioned between the spaced apart extensions.

Figs. 10 and 11 show the extensions or reflanges 7—8 bent inwardly and secured to a hinge butt 18 having perforations 19 for a hinge pin. This butt is secured to the flange 2 (at 20 and 21) on opposite sides of the extensions. This butt is also secured to the body of the door by rivet 22. By this arrangement a cooperation of all the adjacent elements is secured.

While I have shown and described a construction as used in a hopper door made of a rolled steel metallic plate, my construction may also be used in a cast metal hopper door and would have the same advantages as enumerated herein.

The drawings illustrate the preferred form of the invention, though it is to be understood that the invention is not limited to the exact details of construction shown and described, as it is obvious that various modifications thereof within the scope of the claims will occur to persons skilled in the art.

I claim:

1. The combination of a hopper door having a flange with a portion thereof split from the body of the door and bent to form a reflange, and a transverse beam secured to said reflange.

2. The combination of a hopper door having a flange with a portion thereof split from the body of the door and bent to form a reflange, and a transverse beam secured to the body of the door and secured to said reflange.

3. The combination of a hopper door having a flange with a portion thereof split from

the body of the door and bent outwardly to form a reflange, and a transverse beam projecting therebeyond and secured to said reflange.

5 4. The combination of a hopper door having a flange with a portion thereof split from the body of the door and bent outwardly to form a reflange, and a transverse beam secured to the body of the door and projecting therebeyond and secured to said reflange.

10 5. The combination of a hopper door having a flange with a portion thereof split from the body of the door and bent to form spaced apart reflanges, and a transverse beam secured to both of said reflanges.

15 6. The combination of a hopper door having a flange with a portion thereof split from the body of the door and bent to form spaced apart reflanges, and a transverse beam comprising spaced apart arms, each secured to one of said reflanges.

20 7. The combination of a hopper door having a flange with a portion thereof split from the body of the door and bent to form a reflange, and a transverse beam secured to the body of the door and projecting therebeyond.

25 8. The combination of a hopper door having a flange with a portion thereof split from the body of the door and bent to form spaced apart reflanges, and a transverse beam secured to the body of the door and projecting therebeyond, said beam being positioned between the reflanges.

30 9. In a railway car having a door which is swingable to discharge part of the lading, said door comprising a body portion provided with a flange with a part thereof omitted to form an opening, and a beam secured to said body portion extending through said opening and projecting therebeyond, said flange formed with a reflange parallel to and adjacent to said beam.

35 10. In a railway car having a door which is swingable to discharge part of the lading, said door comprising a body portion provided with a flange with a part thereof omitted to form an opening, and a beam secured to said body portion extending through said opening and projecting therebeyond, said

flange formed with a reflange parallel to and 50 secured to said beam.

11. In a railway car having a door which is swingable to discharge part of the lading, said door comprising a body portion provided with a flange with a part thereof omitted to form an opening, and a beam secured to said body portion extending through said opening and projecting therebeyond, said flange formed with spaced apart reflanges 55 parallel to and adjacent to the opposite sides 60 of said beam.

12. In a railway car having a door which is swingable to discharge part of the lading, said door comprising a body portion provided with a flange with a part thereof omitted to form an opening, and a beam secured to said body portion extending through said opening and projecting therebeyond, said flange formed with spaced apart reflanges 65 parallel to and secured to the opposite sides 70 of said beam.

13. In a railway car having a door which is swingable to discharge part of the lading, said door comprising a body portion provided with a flange with a part thereof omitted to form an opening, and a beam secured to said body portion extending through said opening and projecting therebeyond, said flange formed with a reflange parallel to and 75 adjacent to said beam, said flange and said beam provided with registering apertures for the reception of a hinge pin.

14. In a railway car having a door which is swingable to discharge part of the lading, and a beam secured to the body portion of the 85 door, said door provided with a flange having a lateral extension to which the beam is secured.

15. In a railway car having a door which is swingable to discharge part of the lading, 90 said door comprising a body portion provided with flanges adjacent its opposite sides having parts thereof omitted to form openings, and a beam secured to said body portion extending through said openings and 95 projecting therebeyond, each of said flanges formed with a reflange secured to said beam.

ARTHUR E. SMALL.
